UNITED STATES PATENT OFFICE.

HENRY W. HARTEL, OF PHILADELPHIA, PENNSYLVANIA.

LOCK SWITCH.

Application filed June 22, 1921. Serial No. 479,539.

To all whom it may concern:

Be it known that I, HENRY W. HARTEL, a citizen of the United States, residing in Philadelphia, Pennsylvania, have invented certain Improvements in Lock Switches, of which the following is a specification.

My invention relates to electric switches, and more particularly to improvements in that type of electric switches which include 10 means for retaining the blade in the closed or thrown position, means also being provided for releasing the said blade from the locking means when it is desired to open the switch.

15 The object of my invention is to provide a locking device which combines efficiency of operation, extreme simplicity and low cost of manufacture, and which is capable of successful application to double as well 20 as single throw switches.

The invention will be more readily understood by reference to the attached drawings, in which:

Figure 1, is a side elevation of a switch 25 structure equipped with my locking device;

Fig. 2, is a fragmentary side elevation of one end of the switch, enlarged to show the details of the locking device;

Fig. 3, is a fragmentary perspective of 30 the end of the switch blade and of the releasing element carried thereby;

Fig. 4, is a fragmentary perspective of one of the fixed elements of the switch and of the locking elements;

35 Fig. 5, is a fragmentary side elevation illustrating a modification of my locking device;

Fig. 6, is an end view of the said modified form;

40 Fig. 7, is a plan view of that portion of the device illustrated in Fig. 5, and

Fig. 8, is a section taken on the line 8—8, 45 Fig. 5.

In Fig. 1, I have illustrated a well known type of double throw switch comprising a 50 base 1, to one side of which are suitably secured, respectively at the center and at each end, three fixed switch elements 2, 3 and 4, the said intermediate element 3 hav-

ing pivotally secured thereto a blade 5 which is adapted in the extreme positions thereof, one of which positions it occupies in Fig. 1, to engage respectively the said fixed elements 2 and 4.

55 Secured to the base 1 in suitable manner, outwardly of each of the elements 2 and 4,

is a locking member 6, said members each comprising in the present instance a pair of spaced resilient elements 7, 7, disposed substantially perpendicularly to the plane of the base, and having their outer portions 60 offset, in the present instance outwardly, from the under portions and turned inwardly at the top toward the respective switch elements 2 and 4, said elements being 65 flexible in a direction parallel to the plane of the face of said blade 5.

Extending through the outer end of the blade 5 is a pin or dowel 9 which projects at each side beyond the face of the blade 70 and which when the blade is thrown into engagement with either of the elements 2 or 4 is adapted to underlie the shoulders 10, 10, of the adjacent locking elements 7, which shoulders are formed by reason of 75 the aforesaid offset outer portions of the said elements, whereby the blade is retained in engagement with the switch element until such time as the said elements 7 are flexed inwardly to release the dowel. As the blade 80 is moved toward its thrown position, the said dowel first meets the outer ends of the inturned upper portions of the locking elements 7, which elements by the continued movement of the blade are flexed inwardly 85 until the dowel passes the lower end of the said offset upper portions of the locking elements, whereupon the latter spring outwardly to their normal positions with the shoulders 10 overlying the ends of the said 90 dowel, thereby locking the switch blade in place. It will be noted that the blade does not come in contact with the retaining elements, the contact being confined entirely to the dowel, and that, furthermore, by employing in the locking device projections from the sides of the blade and intermediate the ends thereof, I am able to employ locking elements movable in the direction of the length of the blade for both locking 100 and releasing operations, without increasing the overall length of the blade, this direction of movement of the elements in releasing the blade possessing certain well known advantages.

Pivotedly mounted upon the said dowel 9 and comprising a pair of forks 12, 12, which are disposed one on each side of the end of the said switch blade and through which forks the said dowel passes, is a releasing member 13, said member having extending outwardly from each of the said 110

forks and disposed one on each side of the dowel 9, a pair of pins or lugs, 14 and 15, said pins when the switch blade has been thrown to either extreme and is locked in place, assuming the relative positions illustrated in Fig. 1, one or other of said pins, as the case may be, lying against the outer portion 8 of each of the said locking elements 7. The natural strength of the said 10 elements 7 will normally retain the outer end of the releasing member in an elevated position, (see Fig. 2), but when the outer end of the said member is pulled downwardly or outwardly from the base by force 15 exerted thereon, it will be apparent that the said pins which rest against upper portions 8 of the elements 7 will move inwardly of the end of the blade and will thereby force the locking elements to the positions shown 20 in dotted lines in Fig. 2, whereby the said dowel is released and the blade left free to be pulled away from the element 2 or 4, as the case may be, to open the switch. In the present instance, I have shown the 25 outer end of the said releasing member apertured for the reception of a hook or the like.

It is apparent that where a single throw switch is employed, but one of the pins 14, 30 15, will be required, but where a double throw switch is equipped with the device, the two sets of pins are essential, since when the switch blade is in the thrown position, opposite to that shown in Fig. 1, the pins 35 14 will assume a position corresponding to that of the pins 15 in said Fig. 1, and the pin 15 will then be the one actively employed in flexing the element 7 to release the blade.

40 In Figs. 5, 6, 7 and 8, I have illustrated a modification of the device within the scope of the invention. In this case the locking member 6^a is of somewhat different form from the locking member 6 of the previously 45 described preferred form, the difference residing principally in the fact that the resilient elements 7^a, 7^b, which extend upwardly one on each side of the blade or of the path thereof, are flexible in a direction substantially at right angles to the plane of the blade and are movable in engaging and disengaging the dowel 9^a directly toward and away from the faces of the blade instead of as in the previously described form in a direction parallel to the planes of said faces. 50 Also the said resilient elements instead of being provided with shoulders for engagement of the ends of said dowel 9^a are apertured, the said ends of the dowel being 55 adapted to enter the apertures designated in the drawings by the reference numeral 10^a and thereby to be retained.

In this modification furthermore the releasing element 13^a, which is pivotally

65 mounted upon the dowel 9^a in the same manner as the previously described and corresponding releasing element 13, is of somewhat different form than the releasing element 13, there being instead of the projecting elements 14 and 15, suitable enlargements or projections 14^a, 14^b, one at each side of the said releasing element which, by engagement with suitably formed surfaces of the elements 7^a, are adapted under 70 certain circumstances to force the said elements 7^a away from each other to the extent that the ends of the dowel 9^a are cleared by the said elements and the blade 5^a released. The construction by means of which this 75 effect is accomplished is most clearly shown 80 in the drawings, the outer edges of the said elements 7^a, 7^b, being flared outwardly and shaped to form pockets 15^a, 15^b, are, when the blade is in the locked position, occupied 85 by the said projections 14^a at the sides of the releasing element 13^a.

The natural resiliency of the elements 7^a, 7^b, tends to retain them in a position such that the ends of the dowel 9^a are retained in the apertures 10^a, but when the element 13^a 90 is moved downwardly, reference being had to Figs. 5 and 6 of the drawings, or away from the base 1^a of the switch structure, the said enlargements 14^a in being drawn out of the pockets 15^a, 15^b, have the effect 95 of spreading the said elements outwardly so that the dowel is released, as in the manner previously described, thereby permitting withdrawal of the blade 5^a from the switch element 2^a.

100 The outer ends 8^a, 8^b, of the elements 7^a are flared outwardly away from each other and are so disposed that as the blade 5^a is moved into engagement with the switch element 2^a, the said outer ends are engaged by the ends of the dowel 9^a, and as the inward movement of the blade continues, are spread apart thereby until the said ends of the dowel 9^a are advanced into a position opposite said apertures 10^a, whereupon the elements 7^a, 7^b, spring together and securely 105 lock the blade in position.

110 The device in either form is an extremely simple one, can be manufactured at a very low cost, is thoroughly efficient in operation, 115 and has the advantage of being applicable without change or variation to both single or double throw switches.

I claim:

120 1. In an electric switch, the combination with a relatively fixed element, of a movable element adapted to be shifted into and out of engagement therewith, a projection upon said movable element, a relatively fixed locking member including movable means for engaging and retaining said projection when the said movable element is shifted 125 into engagement with the said fixed element,

- and means mounted upon the said projection for shifting said retaining means to release the projection.
2. In an electric switch, the combination with a relatively fixed element, of a movable element adapted to be shifted into and out of engagement therewith, a projection upon said movable element, a relatively fixed locking member including means movable in a direction parallel to the plane of said movable element for engaging and retaining said projection when the said movable element is shifted into engagement with the said fixed element, and means mounted upon the said projection for shifting said retaining means to release the projection.
3. In an electric switch, the combination with a relatively fixed element, of a movable element adapted to be shifted into and out of engagement therewith, a projection upon said movable element, a relatively fixed locking member including resilient means for engaging and retaining said projection when the said movable element is shifted into engagement with the said fixed element, and means mounted upon the said projection for flexing the resilient retaining means to release the said projection.
4. In an electric switch, the combination with a relatively fixed element, of a movable blade adapted to be shifted into and out of engagement therewith, a projection intermediate the extremities of the blade and extending outwardly from the face thereof, a relatively fixed locking member including movable means for engaging and retaining said projection when the blade is shifted into engagement with the said fixed element, and a releasing element mounted upon the projection and adapted to engage and shift the said retaining means to release the projection.
5. In an electric switch, the combination with a relatively fixed element, of a movable blade adapted to be shifted into and out of engagement therewith, a dowel fixed in said blade intermediate the extremities and projecting from the face thereof, a relatively fixed locking member including movable means for engaging and retaining the dowel when the blade is shifted into engagement with the said fixed element, and an element pivotally mounted upon the dowel and adapted to engage and shift the said retaining means to release the said projection.
6. In an electric switch, the combination with a relatively fixed element, of a movable blade adapted to be shifted into and out of engagement therewith, a relatively fixed member disposed adjacent the face and intermediate the extremities of the blade when the latter lies in engagement with the said fixed element and including a movable locking element, a projection from the said adjacent face cooperating with said movable locking element whereby the projection may be releasably retained and releasing means mounted upon the projection.
7. In an electric switch, the combination with a relatively fixed terminal, of a blade adapted to be shifted into and out of engagement therewith, a relatively fixed locking member comprising a pair of movable elements adapted when the blade engages the terminal to lie one on each side of said blade, projections at the sides of the blade cooperating with said movable locking elements whereby the projections are retained by said locking elements, and means carried by the blade for shifting said elements to release the said projections.
8. In an electric switch, the combination with a base, of a fixed terminal secured thereto, a blade pivotally mounted on said base and adapted to be shifted into and out of engagement with the terminal, a lateral projection on the side of said blade, a resilient locking element extending outwardly from said base and disposed adjacent the side of the blade when the latter lies in engagement with the terminal, said element having a shoulder behind which the said projection is adapted to lie whereby the said blade is locked in engagement with the terminal, and a releasing element pivoted to the blade and having a projection adapted when the said element is moved away from the base to engage the upper portion of said resilient element and to flex said element to shift the shoulder clear of said blade projection.
9. In an electric switch, the combination with a base, of a fixed terminal secured thereto, a blade pivotally mounted on said base and adapted to be shifted into and out of engagement with said terminal, a locking member secured to said base and comprising a pair of resilient elements adapted to lie one on each side of said blade when the latter is in engagement with said terminal, a projection at each side of the blade adapted to be engaged by said resilient elements when the blade is in engagement with the terminal and to be retained thereby whereby the said blade is locked in the said engagement, and a release member pivotally mounted on said projections and adapted when the said release element is moved away from the base to engage the said resilient elements and to flex said resilient elements to release the pins.
10. In an electric switch, the combination with a base, of a blade pivotally mounted intermediate the ends of said base, a fixed terminal at each side of said base adapted to engage the blade in the respective extreme positions thereof, a member attached to the base adjacent each of said terminals and including a movable locking element, a projection at the side of said blade adapted in the said extreme positions to be engaged and retained

by the respective locking elements, and a releasing element pivotally secured to said blade and including a pair of spaced elements adapted respectively to engage and to shift the said locking elements to effect the release of said blade projection therefrom.

11. In an electric switch, the combination with a relatively fixed element, of a movable element adapted to be shifted into and out of engagement therewith, a projection upon said movable element, a relatively fixed locking member including resilient means for engaging and retaining said projection when the said movable element is shifted into engagement with the said fixed element, said projection when the said movable element is shifted into engagement with said fixed element being adapted to engage and flex said resilient means to permit the said projection to move into the retained position, and thereafter to release the said resilient means to permit its return to the normal retaining position, and means carried by said movable switch element for flexing the resilient retaining means to release the said projection.

12. In an electric switch, the combination with a relatively fixed element, of a movable element adapted to be shifted into and out of engagement therewith, a projection upon said movable element, a relatively fixed locking member including means movable toward said movable element for engaging and retaining said projection when the said movable element is shifted into engagement with the said fixed element and movable away from said movable element when the latter is to be released, and means mounted upon the said projection for shifting the retaining means outwardly from the movable switch element to release the projection.

13. In an electric switch, the combination with a relatively fixed element, of a movable element adapted to be shifted into and out of engagement therewith, a transversely extending projection upon said movable element, a relatively fixed locking member including movable means for engaging and retaining said projection when the said movable element is shifted into engagement with the said fixed element, and means pivotally mounted upon said movable element for shifting said retaining means to release the projection.

14. In combination, a stationary contact element, a co-acting movable contact element having transversely extending projections, means cooperating with said projections for releasably locking said movable contact member when the same is in engagement with said stationary contact member, and means pivotally mounted on said movable contact member and provided with a projection operable to release said locking means upon a movement of said pivotally mounted means.

15. In combination, a pair of spaced stationary contact elements, a movable contact member co-acting with said stationary contact member, said movable contact member being provided with a projection, means cooperating with said projection for releasably locking said movable contact member when the same is in engagement with one or the other of said stationary contact members, and means pivotally mounted on said movable contact member having projecting means operable to release the locking means upon a movement of said pivotally mounted means.

HENRY W. HARTEL.
